(57) **CLAIM**

The ornamental design for a cushion assembly for breathing mask assembly, as shown and described.

DESCRIPTION

FIG. 1 is a front, top, and side perspective view of a cushion assembly for breathing mask assembly embodying our new design;

FIG. 2 is a rear, top, and side perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof; and,

FIG. 9 is a cross-sectional view taken along line 9-9 of FIG. 3.

Broken lines are used to illustrate portions of the cushion assembly for breathing mask assembly that form no part of the claimed design.
